United States Patent Office.

THOMAS C. HENDRY, OF UNION POINT, GEORGIA.

Letters Patent No. 74,356, dated February 11, 1868.

IMPROVEMENT IN COMBINED SQUARE AND GAUGE.

The Schedule referred to in these Letters Patent and making part of the same.

TO ALL WHOM IT MAY CONCERN:

Be it known that I, THOMAS C. HENDRY, of Union Point, in the county of Green, and State of Georgia, have invented a new and improved Combined Square and Gauge; and I do hereby declare that the following is a full, clear, and exact description thereof, which will enable others skilled in the art to make and use the same, reference being had to the accompanying drawings, forming a part of this specification, in which—

Figure 1 is a side view of my square and gauge.

Figure 2 is a section of the same, through the line $x x'$.

Similar letters of reference indicate corresponding parts.

The nature of this invention consists in combining a gauging-device with a common carpenter's square.

A and B are the arms of a square. In the shorter arm B is a slot, d, running nearly its whole length, the said slot having V-shaped edges, as shown at fig. 2. A sliding butt, consisting of two plates $\alpha \alpha$, held together by a screw, b, fits into the said slot d, and is movable to and fro in the slot, the friction of the same being adjusted by the screw b. A plate, e, having a point, i, is secured to the square at the junction of the two arms. The point i can be made the initial point of measurement on the slotted arm if desired. A similar plate and point are placed on the opposite side of the square at the same point. The plates $\alpha \alpha$ have each a point, $i' i'$, on a line with the points $i i$, and, together with the latter, serve as a gauge for striking lines in the ordinary manner. At the extremity of the slot is an opening, C, by means of which the plates $\alpha \alpha$ are removed from the square, or attached to the same without taking the said plates apart, it being only required to loosen them a little when inserting them again. This improved combination dispenses with the use of the common gauge, and provides a cheap, convenient, and useful tool.

I am aware that movable points have been patented, but the points were attached to a T-square, and were intended only as a substitute for dividers, and were properly a draughting-instrument.

Having thus described my invention, what I claim as new, and desire to secure by Letters Patent, is—

The combination of gauge-points i and i' with an arm of a common square, by means of a slot, d, and plates $\alpha \alpha$, or other equivalent device, substantially as shown and described, and for the purpose specified.

THOMAS C. HENDRY.
